APPARATUS FOR CONTROL OF HIGHWAY
CROSSING SIGNALS

Ronald A. McCann, Swissvale, Pa., assignor to
The Union Switch & Signal Company, Swiss-
vale, Pa., a corporation of Pennsylvania

Application April 25, 1942, Serial No. 440,520

6 Claims. (Cl. 246—130)

My invention relates to apparatus for control of highway crossing signals, and more particularly to apparatus for control of warning signals associated with a highway crossing gate.

Highway crossing gates are frequently controlled automatically by railway traffic and the warning signals, either visual or audible, or both, associated therewith are usually controlled by the same approach track circuit that controls the gates. When this is so, the warning signals are operated only when the gates are being lowered due to a train approaching the highway crossing, and the lowering of a gate for any other reason, such as an inspection test, failure of the gate mechanism or failure of a control circuit, may not be accompanied by a warning signal, with the result that highway users may be given no warning and the gate arm may be lowered directly in front of or on top of a highway vehicle.

A feature of my invention is the provision of improved means for control of a warning signal associated with a highway crossing gate and wherewith operation of the warning signal when the gate arm is being lowered for any reason is assured.

Another feature of my invention is the provision of improved means for operating a warning signal independent of the approach track circuit that governs a highway crossing gate.

Other features and objects of my invention will appear as the specification progresses.

I shall describe two forms of apparatus embodying my invention, and shall then point out the novel features thereof in claims.

In the accompanying drawings, Fig. 1 is a diagrammatic view showing one form of apparatus embodying the invention when used with a gate mechanism provided with a slot magnet having circuit controlling contacts attached to its armature. Fig. 2 is a diagrammatic view showing another form of apparatus embodying my invention when used with a gate mechanism controlled over contacts of an associated control relay. In each of the two views like reference characters are used to designate similar parts.

It will be understood that my invention is not limited to apparatus for a warning signal at a highway crossing gate automatically operated, but is useful when the gate is manually controlled, or when the gate is controlled in part manually and in part by railway traffic. Also the invention is not limited to gates that are gravity biased to the lowered position and motor oper-

ated to the raised position, but is useful where the gate is power operated both up and down.

Referring to Fig. 1, the reference characters 1a and 1b designate the track rails of a railway 5 intersected at grade by a highway H and at which intersection two highway crossing gates G1 and G2 are located. The track rails 1a and 1b are formed by the usual insulated rail joints with two track sections D—E and E—F, section D—E 10 extending to the left of highway H as viewed in the drawings, and section E—F extending to the right of the highway. Each section D—E and E—F is provided with a track circuit which includes a current source, such as a battery 10, 15 connected across the rails at one end of the section, and a winding of an interlocking relay IR connected across the rails at the other end of the section, winding 11 of relay IR being included in the track circuit of section D—E and winding 20 12 of relay IR being included in the track circuit of section E—F. The connections of windings 11 and 12 of relay IR to the track rails are those commonly used to provide the so-called "extended shunt" protection, and these connections need not be described in detail since they 25 form no part of my invention.

The highway crossing gates G1 and G2 are shown conventionally and are located one on each side of the railway track and are operated in a 30 manner such that the respective gate arms 13 and 14 are moved between a lowered position where the arm extends horizontally across at least a portion of highway H to obstruct highway traffic approaching the intersection, and 35 a raised position where the arm extends substantially vertically to clear highway traffic. Each crossing gate G1 and G2 is provided with an operating mechanism which may be any one of several constructions, and preferably the two 40 mechanisms are of like construction. In the present embodiment of my invention, the gate mechanism is similar to that shown and described in Letters Patent of the United States No. 1,138,087, granted May 4, 1915 to John P. 45 Coleman, for Railway signals. In the present application the gate arm is an extended form of the semaphore of the patent. The mechanism and control means for gate G1 only is shown in Fig. 1, for the sake of simplicity, since that for gate G2 would be but a duplication of that for gate G1.

The gate G1 mechanism includes as essential elements, a motor M1, a slot magnet SM and a circuit controller C1. Motor M1, which 50 comprises an armature 15 and a field winding 16 is

operatively connected by suitable drive mechanism not shown, to the gate arm 13, arm 13 being biased by gravity to its lowered position and driven to its raised position when motor M1 is energized. In the following description the lowered position of the gate arm will be considered as a zero degree position, and the raised position of the arm will be considered as a 90 degree position.

Slot magnet SM includes a holding winding 17 and a pick-up winding 18, the arrangement being such that energization of both windings 17 and 18 is required to pick up the armature of the slot magnet, but that once the armature is picked up, then energization of holding winding 17 alone is sufficient to retain the armature picked up. When the armature of the slot magnet SM is picked up, it latches the gate mechanism at the 90 degree position. Furthermore, slot magnet SM is provided with circuit controlling contacts which are attached to its armature in the usual well-known manner.

Circuit controller C1 is operatively connected with the mechanism for governing circuit controlling contacts according to the position of the mechanism, three contacts 4, 7 and 9 being shown conventionally and operated according to the legends placed in the drawings.

A warning signal is associated with gate G1 and as shown in Fig. 1, it is an audible signal in the form of an electric bell B1. It is to be understood, however, that my invention is not limited to an audible signal, but that a visual signal in the form of a color light or flashing lights, or a combination of a visual signal and an audible signal may be used. Bell B1 is provided with two operating circuits, a first one of which passes from terminal B of any convenient source of current, such as a battery not shown, through either full-down flagman contact 22 of relay IR or front flagman contact 20 and full-down contact 23 of relay IR, contact 7 of controller C1 of the gate mechanism, and the winding of bell B1 to terminal C of the source of current. The second operating circuit is from terminal B, through contact 4 of controller C1, back contact 24 of slot magnet SM, controller contact 7, and winding of bell B1 to terminal C. It is apparent that bell B1 will be operated whenever a train approaching the intersection releases either winding of the interlocking relay IR, and also whenever slot magnet SM is released to close back contact 24, operation of the bell due to the release of magnet SM being independent of the operation effected by interlocking relay IR.

The apparatus also includes a slow release control relay XR which is provided with a circuit including in series the two front flagman contacts 19 and 20 of interlocking relay IR. Relay XR in turn controls at its front contact 21 simple energizing circuits for windings 17 and 18 of the slot magnet SM, the circuit for winding 18 also including contact 9 of controller C1.

Normally, that is, when both track sections D—E and E—F are unoccupied, both windings 11 and 12 of interlocking relay IR are energized, causing control relay XR and in turn the holding winding 17 of slot magnet SM to be energized with the result that the gate is latched at its 90 degree position. Warning bell B1 is now silent because both of its operating circuits are open. When a train approaching the intersection enters either section D—E or E—F, releasing either winding 11 or 12 of relay IR, the closing of full-down contact 22 or 23 of relay IR

will complete the first operating circuit for bell B1 and the bell will be sounded as a warning to highway users of the approach of the train and that the gate is about to be lowered. Control relay XB is also deenergized upon the opening of either front contact 19 or 20 of the interlocking relay, and relay XR is released at the end of its slow release period to open the energizing circuit of holding winding 17 of slot magnet SM so that the gate then moves to its lowered position. Release of slot magnet SM closes at back contact 24 the second operating circuit for bell B1 but this second circuit performs no useful function at this time because the bell is already being operated over its first circuit. It is to be pointed out that when the gate arm is lowered to nearly the zero degree position, operation of the bell is discontinued due to the opening of controller contact 7. When the train clears the intersection, the previously deenergized winding 11 or 12 of the interlocking relay is reenergized to close its front flagman contact 19 or 20 so that relay XR is reenergized causing both windings 17 and 18 of the slot magnet SM to be energized and the armature of the slot magnet to be picked up. A motor operating circuit is now completed from terminal B through controller contact 4, front contacts 25 and 26 in multiple of slot magnet SM, and armature 15 and field winding 16 of motor M1 to terminal C, so that the motor is operated as required to raise the gate. At the 89 degree position, the motor operating circuit is opened at contact 4 and the circuit for winding 18 of slot magnet SM is opened at contact 9, but the gate is latched in the raised position due to the energization of holding winding 17.

Lowering of gate G1 due to the release of slot magnet SM for any reason other than the control effected by a train through the track circuits is accompanied by an operation of the warning signal, bell B1 being operated through its second circuit including back contact 24 of slot magnet SM. Deenergization of slot magnet SM and a lowering of the gate while the track circuits are unoccupied and relay IR is picked up may be brought about due to a test operation, or due to a failure of a control circuit or of the gate mechanism.

It is to be observed that motor M1 is driven backward during the lowering of the gate and regenerative braking provided through a low resistance shunt path completed through the motor at back contacts 36 and 37 in multiple of slot magnet SM.

It is to be seen therefore that with the apparatus disclosed in Fig. 1, the warning signal B1 is operated by a first circuit when the gate is lowered due to the approach of a train, and is operated by a second circuit when the gate is lowered due to some failure of the apparatus or other condition, the operation by the second circuit being independent of the track circuit control.

Referring to Fig. 2, the track circuits are the same as in Fig. 1. Furthermore, gate G1 mechanism of Fig. 2 is similar to that of Fig. 1 except that the contacts attached to the armature of the slot magnet SM are omitted, additional contacts are included in controller C1, and the motor M1 is provided with a so-called "snubbing" relay SR for control of a low resistance shunt path, connected across the motor for regenerative braking during the lowering of the gate arm. The apparatus of Fig. 2 includes three control relays XR, TPR and GPR. Relay XR is controlled over front

flagman contacts 19 and 20 of relay IR as in Fig. 1, but relay XR of Fig. 2 is preferably not of the slow release type. Relay TPR is a slow release repeater relay controlled over a simple circuit including in series the front flagman contacts 27 and 28 of interlocking relay IR. Relay GPR is controlled by a circuit passing from terminal B, through front contacts 29 and 30 in multiple of relay XR, contact 2 of controller C1, and winding of relay GPR to terminal C.

Normally, that is, when the track circuits are unoccupied by a train approaching the intersection, control relays XR, TPR and GPR are all picked up. The front contact 31 of relay TPR then completes a simple circuit for holding winding 17 of slot magnet SM so that the gate mechanism is latched at its 90 degree position. Bell B1 is normally silent.

A train approaching the intersection of Fig. 2 from either direction causes the corresponding winding of relay IR to be deenergized, and the closing of either full-down contact 22 or 23 of relay IR completes a first operating circuit for bell B1 through contact 7, so that the bell is sounded as a warning that the gate is about to be lowered. Relay XR is deenergized and releases to open the circuit for relay GPR and to open a motor operating circuit to be shortly explained. Relay TPR is also deenergized and releases at the end of its slow release period to deenergize the slot magnet SM and permit the gate to gravitate to its lowered position. Motor M1 is driven backwards during the downward movement of the gate and regenerative braking of the gate mechanism is provided due to a low resistance shunt path completed through back contact 32 of relay SR, contact 5 of controller C1, and a portion of a resistor 33. Just before the zero degree position of the gate arm is reached, the operation of the bell B1 is discontinued due to contact 7 opening the operating circuit for the bell. When the train clears the intersection to permit relay IR to reclose its flagman contacts, the two relays XR and TPR are reenergized and picked up. The picking up of relay TPR energizes winding 17 of slot magnet SM. The picking up of relay XR to close its front contacts 29 and 30 completes a motor operating circuit through contact 4 of controller C1, winding of relay SR, and armature 15 and field winding 16 of motor M1 to terminal C of the current source. Relay SR is thus energized and picked up to open back contact 32 and so remove the low resistance path across the motor M1, and the motor is operated to raise the gate arm. At the 86 degree position of the movement of the gate, contacts 2 and 3 are closed, the closing of contact 2 completing the circuit for relay GPR to pick up that relay. The closing of contact 3 completes the circuit for winding 18 of slot magnet SM, the circuit passing from terminal B through front contacts 29 and 30 in multiple of relay XR, contacts 4 and 3 in series and winding 18 to terminal C. Both windings 17 and 18 of the slot magnet being now energized, its armature is picked up so that the gate mechanism is latched in the 90 degree position when the motor operating circuit and the circuit for winding 18 are opened at contact 4 of the controller C1.

In the event slot magnet SM becomes deenergized for any reason other than the control effected by interlocking relay IR, the gate starts to gravitate to its lowered position, and at the 86 degree position relay GPR is released to close back contact 34 and complete a second operating

circuit for bell B1, such operating circuit also including back contact 35 of relay SR, and contact 7 of controller C1. Thus bell B1 is sounded as a warning indication that the gate is being lowered whenever the magnet SM is deenergized to unlatch the gate mechanism.

It is to be pointed out that in both Figs. 1 and 2, bell B1 is silent during the operation of raising the gate. In Fig. 1, the first operating circuit for bell B1 is held open at the back contacts 22 and 23 of relay IR and the second circuit is held open at back contact 24 of slot magnet SM during this operation. In Fig. 2, the first operating circuit for bell B1 is held open at the back contacts of relay IR, the same as in Fig. 1, and the second operating circuit is held open at back contact 35 of relay SR. It is to be observed that in Fig. 2, if it is desired that the bell B1 be sounded during the raising of the gate, the back contact 35 of relay SR would be omitted from the second operating circuit for the bell and the bell would be operated by the second operating circuit until the 86 degree position of the movement is reached, at which point relay GPR is picked up to open the bell circuit at back contact 34.

The apparatus disclosed in Fig. 2 has the same desirable advantages as the apparatus of Fig. 1, in that the warning signal is operated when the associated gate is being lowered irrespective of the circumstances that cause the gate to be lowered. Consequently the possibility of the gate arm being lowered immediately in front of or on top of a highway vehicle is minimized by the apparatus here disclosed.

Although I have herein shown and described but two forms of highway crossing signal control apparatus embodying my invention, it is understood that various changes and modifications may be made therein within the scope of the appended claims without departing from the spirit and scope of my invention.

Having thus described my invention, what I claim is:

1. In combination, a highway crossing gate located at an intersection of a railway and a highway, a warning signal located to provide at times a warning indication to highway traffic approaching said intersection, electromagnetic means to govern said gate to its clear or obstructing position according as said electromagnetic means is energized or deenergized, circuit means controlled by railway traffic to energize or deenergize said electromagnetic means according as a train is not or is approaching the intersection, a first operating circuit controlled by said circuit means to operate said signal to give its warning indication when a train approaches the intersection, and a second operating circuit controlled by said electromagnetic means when deenergized to operate said signal to give its warning indication.

2. In combination, a highway crossing gate located at an intersection of a railway and a highway and provided with an arm movable either to a lowered position where it obstructs highway traffic or to a raised position where it clears highway traffic, a slot magnet for said gate to latch the arm at its raised position when the magnet is energized and to permit the arm to move to its lowered position when the magnet is deenergized, railway traffic controlled means to energize or deenergize said slot magnet according as a train is not or is approaching said intersection, a warning signal at said intersection active at times to give a warning indication but normally inactive, a first circuit means governed by said

railway traffic controlled means when a train is approaching the intersection to render said signal active, and a second circuit means including a back contact controlled by said slot magnet to render said signal active independent of said railway traffic controlled means.

3. In combination, a highway crossing gate located at an intersection of a railway and a highway and provided with an arm movable to either a lowered position to obstruct highway traffic or to a raised position to clear highway traffic, a slot magnet for said gate, a track circuit including a track relay responsive to railway traffic approaching said intersection, an electric bell at said gate for sounding a warning when the gate arm is being lowered, a first circuit including a front contact of said track relay to energize said slot magnet, a second circuit including a back contact of said track relay to operate said bell, and a third circuit including a back contact of said slot magnet to operate said bell independent of said second circuit.

4. In combination, a highway crossing gate located at an intersection of a railway and a highway and provided with an arm movable to either a lowered position to obstruct highway traffic or to a raised position to clear highway traffic, a track circuit including a track relay responsive to railway traffic approaching said intersection, an electric bell at said gate to sound an alarm, control relay means, means controlled by said control relay means to retain said gate arm at its raised position when the control relay means is energized and to permit the lowering of the gate arm when the control relay means is deenergized, means including a front contact of said track relay to energize said control relay means, a first operating circuit including a back contact of said track relay to operate said bell, and a second operating circuit including a contact governed by said control relay means when deenergized to operate said bell independent of said first operating circuit.

5. In combination, a highway crossing gate lo-

cated at an intersection of a railway and a highway and provided with an arm movable to either a lowered position to obstruct highway traffic or to a raised position to clear highway traffic, a track circuit including a track relay responsive to railway traffic approaching said intersection, an electric bell, a control relay, motor means governed by said control relay when energized to move the gate arm to its raised position and to permit movement of the arm to its lowered position when said control relay is deenergized, means including a front contact of said track relay to energize said control relay, a first operating circuit including a back contact of said track relay to operate said bell, and a second operating circuit including a contact controlled by said control relay, and a contact governed by said motor means to operate said bell independent of said first operating circuit.

6. In combination, a highway crossing protecting means located at an intersection of a railway and a highway and movable to a first position where it obstructs highway traffic entering the intersection and a second position where it clears highway traffic, electromagnetic means to govern the movement of said protecting means, a warning signal at said intersection, a track circuit including a track relay responsive to railway traffic approaching said intersection, means including a contact of said track relay to control said electromagnetic means to effect the first or the second position of said protecting means according as a train is or is not approaching the intersection, a first operating circuit including a contact of said track relay to operate said warning signal in response to a train approaching the intersection, and a second operating circuit including a contact governed by said electromagnetic means when conditioned to permit movement of said protecting means to its first position to operate said warning signal independent of said first operating circuit.

RONALD A. McCANN.
